LLC(57) **CLAIM**

The ornamental design for a display panel in an assisted reproductive techniques (art) workstation, as shown and described.

DESCRIPTION

FIG. 1 is a front view of a display panel in an assisted reproductive techniques (art) workstation showing my new design; FIG. 2 is a top plan view thereof;

FIG. 3 is a front perspective view thereof;

FIG. 4 is another front perspective view thereof;

FIG. 5 is a right elevational view thereof;

FIG. 6 is a rear view of the top portion thereof; and,

FIG. 7 is a bottom perspective view thereof.

In the drawings, the broken lines depict unclaimed subject matter only and form no part of the claimed design.
